[57] CLAIM

The ornamental design for a suction drain guard for swimming pools, as shown and described.

DESCRIPTION

FIG. 1 is a front isometric view of a suction drain guard for swimming pools embodying my new design;

FIG. 2 is a rear isometric view thereof;

FIG. 3 is a front elevational view thereof;

FIG. 4 is a rear elevational view thereof;

FIG. 5 is a side elevational view thereof, the opposite side being a mirror image of the side shown.

FIG. 1.

FIG. 2.

FIG. 3.

FIG. 4.

FIG. 5.
